UNITED STATES PATENT OFFICE

161,291

PLATE OR SIMILAR ARTICLE

Evan K. Shaw, Los Angeles, Melvin Shaw, Beverly Hills, and Robert Y. Allen, Encino, Calif., assignors to Metlox Manufacturing Company, Manhattan Beach, Calif., a corporation of California

Application April 3, 1950, Serial No. 8,951

Term of patent 14 years

(Cl. D44—15)

To all whom it may concern:

Be it known that we, Robert Y. Allen, residing at Encino, in the county of Los Angeles, State of California, Melvin Shaw, residing at Beverly Hills, in the county of Los Angeles, State of California, and Evan K. Shaw, residing at Los Angeles, in the county of Los Angeles, State of California, have invented a new, original, and ornamental Design for Plate or Similar Article, of which the following is a specification, reference being had to the accompanying drawing, forming part thereof, in which the figure is a face view of a plate or similar article, showing our new design. The dominant features reside in the portions shown in full lines.

We claim:

The ornamental design for a plate or similar article, as shown and described.

EVAN K. SHAW.
MELVIN SHAW.
ROBERT Y. ALLEN.
